[57] **CLAIM**

The ornamental design for a rotary tool, as shown and described.

DESCRIPTION

FIG. 1 is a perspective view of a rotary tool showing my new design.

FIG. 2 is a left side elevational view thereof.

FIG. 3 is a right side elevational view thereof.

FIG. 4 is a top plan view thereof.

FIG. 5 is a bottom plan view thereof.

FIG. 6 is a front elevational view thereof; and,

FIG. 7 is a rear elevational view thereof.

The broken line showing is for illustrative purposes only and forms no part of the claimed design.
